UNITED STATES PATENT OFFICE

150,159

DESIGN FOR AN ASH TRAY

Philip Reynolds, Forest Hills, N. Y.

Application February 24, 1947, Serial No. 137,136

Term of patent 3½ years

(Cl. D85—2)

To all whom it may concern:

Be it known that I, Philip Reynolds, a citizen of the United States, residing at Forest Hills, in the county of Queens and State of New York, have invented a new, original, and ornamental Design for an Ash Tray, of which the following is a specification, reference being had to the accompanying drawing, forming part thereof.

In the drawing, the figure is a perspective view of an ash tray, showing my new design.

I claim:

The ornamental design for an ash tray, as shown.

PHILIP REYNOLDS.
